UNITED STATES PATENT OFFICE.

HANS FÖRSTER, OF NIEDER-ZWONITZ, ERZGEBIRGE, GERMANY.

KNITTING MACHINE.

Application filed March 20, 1925. Serial No. 17,075.

To all whom it may concern:

Be it known that I, HANS FÖRSTER, a citizen of the German Republic, and resident of Nieder-Zwonitz, Erzgebirge, Germany, have invented a new and useful Improvement in Knitting Machines, of which the following is a specification.

My invention relates to knitting machines and is especially intended for use in connection with flat knitting machines such as are employed in making stockings. More particularly the invention concerns an automatic device for performing the welting of the fabric upon flat knitting machines. It has already been proposed to move the means carrying the initial row of loops in a guide-way in such a manner that first the fabric-portion forming the welt is made which is then conveyed to the frame needles. My invention differs from machines of this kind in that the carrier of the initial row of loops is transferred to horizontally swinging arms of a frame and is caught in recesses of said arms whereafter these latter are turned into vertical position and the frame with the suspended carrier is moved again towards the frame needles. In the end position the welting is automatically performed by lowering while the fabric is placed upon the frame.

My invention is illustrated diagrammatically and by way of example in the accompanying drawings in which Figure 1 is a front elevation of a part of a knitting machine according to this invention; Figure 2 is a cross-section therethrough; Figures 3-7 are detail views on an enlarged scale showing the manner of forming the welt; Figure 8 is a perspective view of certain parts of the additional frame drawn also on an enlarged scale; and Figures 9-13 are detail views showing the mechanism for forming the welt.

Referring to Figs. 1 and 2, 1 denotes arms arranged to swing in vertical planes. The lower ends of said arms are hinged to levers 3 fulcrumed at 3^a to the machine frame 22. Each lever 3 carries at its free end a roll 3^b running upon a cam 4^a secured to a shaft 4 also supported in the machine frame 22. The arms 1 can be moved up and down by cams 4^a, and may also be swung forward and rearward by cams 6 and coiled springs 7 respectively. The cams 6 are fixed to a shaft 5 carried by the frame 22, and the springs 7 constantly hold the arms 1 in

contact with said cams 6. Each of the arms 1 is provided with a roll 1^a arranged at the point of contact with the appertaining cam 6. The arms 1 are shown in Fig. 2 in two different positions in full and dotted lines, respectively.

The upper ends of the arms 1 are connected by a horizontal bar 2 having downwardly extending short arms 10 arranged at right angles to said bar and forming the connecting members with the said arms 1.

The shaft 5 carrying the cams 6 is turned in any suitable manner by a ratchet device or the like which is under the control of a pattern-chain or the like.

The arrangement of the arms 1 relatively to the needles 8 is such that the pivots 3^c lie about vertically below the needles 8, and the arrangement of the bar 2 relatively to the jack sinkers 9 is such that the hinges connecting the short arms 10 to the long arms 1 lie below said sinkers. When the arms 1 are in the vertical position and the arms 10 in the horizontal position as shown in dotted lines in Figure 2, the arms 10 arranged in the level of each set or division serve as guides for the holders 11 of the latch welt needles.

A plurality of arms 1 are distributed over the machine to support the bar 2 and prevent bending of same.

The short arms 10 may be coupled to the arms 1 by pawls 12 attached to the arms 10 and capable of engaging suitably arranged notches in the arms 1.

Upon a table 14 take up hooks 15 are arranged at both sides of every set or division. These hooks are actuated by coiled springs 16. In these hooks 15 the rods 17 are held as will be seen best in Fig. 7.

Each of the arms 10 has in its upper face at the rear side a recess 18, Figs. 3-6. With regard to each set or division said recesses are located on the inner side. Each recess 18 is undercut at 19 as best seen in Fig. 3 and the width of said recesses 18 corresponds to the thickness of the holders 11 which can, therefore, enter into the said undercuts, as illustrated in Fig. 7. 20 is the usual take up roller, and 21 the knock over comb. The movements of the parts just described correspond to those taking place during the ordinary covering.

The manner of operation of the entire device is as follows:

After the first row of loops has been sunk

the holder 11 which is provided with latch needles 25 is hung into the loops. The holder 11 is guided by the arms 10 the positions of which at the commencement of the work is shown in Fig. 3. The holder 11 is connected with the take up roller 20 by a band 23 (Figs. 3-5). The take up roller 20 is rotated by means of a fall weight (not shown).

10 During the work, the holder moves upon the arms 10, that is to say, it is pulled by means of the take up roller 20 in the direction indicated by the arrow *x*, Fig. 4, until it arrives over and drops into the recesses 18 (Fig. 5). During this advance of the holder 11 the long arms 1 are moved by the eccentric 6 into the position shown in full lines in Fig. 6, so that the arms 10 will also be in the position shown in full lines. Now 15 the rods 17 are put upon the fabric and the hooks 15 are brought in position whereupon by means of pressure or tension the arms 1, are turned upwards and rearwards as indicated by the arrow *y* so that the holder 11 is caught in the undercuts 19 of the recesses 18. The hook 15 which by means of the spring 16 pulls away from the set or division is thereby attracted and the normal take up is interrupted. By means of the eccentric 6 and the spring 7 the arms 1 are 20 then swung again towards the frame needles 8, and by the further work the welt receives the necessary length until the arms 1 occupy their vertical position in front of the frame needles.

25 30 35 If now by the downward movement of the lever 3 upon the cam 4^a the frame formed by the arms 1, 2 and 10 is lowered the holder 11 carrying the needles arrives between the knock over sinkers which now move the loops over the tongues of the needles, as shown in Figs. 10 and 11. The lowered frame-needles then rise again and enter into the loops of the meshes arranged upon the 40 45 shafts of the comb-needles, whereas the rising comb needles leave the loops (Figs. 12 and 13). From this moment the work proceeds in the normal manner.

I claim:

50 1. In a flat knitting machine means for forming the welt comprising in combination: upwardly extending arms arranged to swing in vertical planes; short arms hinged to said swingable arms, a needle holder arranged to slide upon said short arms; and means for moving all said arms forward and rearward, as well as up and down.
